UNITED STATES PATENT OFFICE

WILLIAM C. MACDONALD, OF MALDEN, MASSACHUSETTS

CLAVICLE APPARATUS

Application filed January 5, 1928. Serial No. 244,686.

This invention relates to new and useful improvements in clavicle apparatus.

Heretofore all devices for maintaining the reduction of fractured clavicle have had in view the forcing of the shoulder joint on the injured side, backward, outward and upward. Such previously used devices are strips of adhesive tapes, and bandages. Both of these devices are defective insofar as the arm is supported from and is subject to the movements of the shoulder of the uninjured side. Adhesive tapes slip and irritate the skin; they cannot be adjusted without removal; they confine the arm unnecessarily, and require frequent change and attention. Bandages are less stable than adhesive tapes; they slip readily from the shoulder, and they stretch easily and require daily attention.

My invention has among its several objects to provide a clavicle apparatus which fulfills all the requirements and eliminates all of the disadvantages of the devices heretofore used; to provide such an apparatus which may be readily applied to either side of a person, and which may be readily adjusted to final position, or removed, and to provide such an apparatus which is simple in construction and cheap to manufacture.

With these and other objects in view which will more fully appear, the nature of the invention will be more clearly understood by following the description, the appended claims, and the several views illustrated in the accompanying drawings.

In the accompanying drawings which illustrate one form of my invention,

Figure 1 is a front elevation showing the application of my invention,

Figure 2 is a rear elevation thereof,

Figure 3 is a perspective view of the forearm sling,

Figure 4 is a perspective view of the metal bow,

Figure 5 is a front elevation, partly in section, of the vest showing the metal bow in position,

Figure 6 is a perspective view of the elbow sling,

Figure 7 is a sectional view of the arm band and axilla pad, and

Figure 8 is a perspective view showing the arm band and the axilla pad in separated relation.

Like reference numerals designate corresponding parts throughout the several figures of the drawings.

Referring in detail to the accompanying drawings, A indicates the half-vest which is positioned on the sound side of the patient, B the vest bow, C the arm band, D the axilla pad, E the elbow sling, and F the forearm sling, the arm band, pad, and both slings being associated with the arm on injured side

The half-vest A is formed of closely woven inelastic material and is constructed to provide a front portion 5, a rear portion 6, and a connecting or shoulder portion 7, the portions forming a resultant arm hole 8. The front and rear portions are adjustably connected by upper and lower side straps 9, 10 secured to the rear portion by stitching and cooperating upper and lower buckles 11, 12 which are to loops 13, 14 stitched to the front portion. A pocket 15 extends upwardly from the lower edge of the front portion 5, thence over the shoulder portion 7, and then downwardly along the rear portion 6 to the lower edge thereof. This pocket is formed from an elongated strip 15^a of material having its longitudinal edges infolded and secured to the front, rear and shoulder portions of the vest by stitches. A belt 16 has one end attached to the lower inner edge of the rear portion 6, the free end being adapted for engagement with a buckle 17 attached to lower part of the front portion 5.

The U-shaped bow B which is inserted within the pocket 15 of the vest, is formed of steel or other metal and is adapted to be bent or twisted to conform to the shape of the patient.

The arm band C is formed of woven inelastic material and is provided at one end with a metal loop 18 and at its other end with an inelastic strap 19. The strap extends laterally across the patient's back as shown in Fig. 2, and has its free end adjustably con-

neeted to a buckle 20 secured to the rear portion 6 of the half-vest A.

The axilla pad D is detachably connected to the arm band C by a pair of snap fasteners, 5 the headed parts 21, 21 thereof being attached to the band and the socket parts 22, 22 being attached to the pad.

The elbow sling E is formed of inelastic material and constructed to provide opposite 10 front and rear side portions 23, 24 which are integrally united to form a substantially horizontal elbow supporting portion 25 and a substantially vertical elbow supporting portion 26. The sling intermediate said portions 15 25 and 26 is formed with an opening 27 to fit the elbow. The front side portion 23 is provided with a pair of laterally extending upper and lower tabs 28, 29, and similarly the rear side portion 24 is provided with 20 upper and lower tabs 30, 31. Attached to the ends of the front tabs are metal loops 32, 33, and extending from the ends of the rear tabs are upper and lower inelastic straps 34, 35 which extend laterally across the chest of the 25 patient, as shown in Fig. 1, and have their ends adjustably connected to lower and upper buckles 36, 37 attached to the front vest portion 5 at different elevations. A strap 38 of inelastic material has one end attached to 30 the sling E at the horizontal elbow supporting portion 26. This strap extends upwardly at an angle across the back of the patient and has its end adjustably connected to a buckle 39 attached to the upper part of the rear portion 35 6 of the vest.

The forearm sling F is also formed of inelastic material and is centrally folded to provide opposite front and back side portions 40, 41. The upper ends of the side portions 40 are held against separation by a strap 42, and a buckle 43 is attached to said strap. A supporting inelastic strap or hanger 44 has its upper end attached to the upper part of the front vest portion 5 and the lower free end of 45 the strap is adjustably connected with the buckle 43 for supporting the forearm of the patient in any desired position.

An inelastic strap 45 similar to the strap 44 is attached at its upper end to the upper part 50 of the rear portion 6 of the vest, thereby permitting the parts of my apparatus to be readily applied to either side of a patient.

In applying my apparatus to a patient, the metal bow B is bent and twisted, if necessary, to fit the contour of the chest. The bow is then inserted within the pocket 15 of the half-vest A, the side straps 9, 10 not being buckled during the insertion. The half-vest A is then placed on the sound side of the patient, and the side straps 9, 10 and the belt 16 are then tightened until the vest and the bow fit the side of the chest. The arm band C is then positioned around the upper arm on the patient's injured side, and the strap 19 is 65 then extended across the back and connected

with the buckle 20. The axilla pad D is positioned under said arm and attached by the fasteners 21, 21 to the arm band C. The elbow sling E is then applied to said arm and secured in position by the front straps 34, 35 and the rear strap 38. During the application of the elbow sling E the elbow is moved slightly inwardly and forwardly in order to throw the shoulder backwardly and outwardly. Sufficient tension is given to the front diagonal strap 35 and to the rear strap 38 to lift the injured shoulder about one inch higher than the opposite side. The forearm sling F is then adjusted in any desired position. All straps are then readjusted, if necessary, using only sufficient tension to keep the shoulder of the injured side in the desired position.

From the foregoing it will be observed that I have provided a half-vest having a metal bow which affords fixed points for the attachment and support of the arm band, elbow sling and forearm sling; that the bow is not supported by the shoulder but is fixed to the side of the chest below the shoulder joint, and that the bow when properly bent does not touch the shoulder but allows free movement of the arm on the well side without disturbing the various adjustments; that the arm band C may be positioned accurately and firmly, serves to hold the shoulder backward, and affords attachment for the axilla pad D; that the elbow sling E serves to hold the elbow inwardly and upwardly in a most effective and comfortable manner, and that the forearm sling F may be raised or lowered independently of the other parts, or may be removed from the arm when the patient is lying down so as to permit the arm to be straightened and thereby prevent stiffness of the elbow joint.

It is of course to be understood that the details of structure and arrangements of parts may be variously changed and modified without departing from the spirit and scope of my invention.

I claim:

1. In a clavicle apparatus, the combination with a half-vest adapted for application to the side of the patient opposite the broken clavicle, said half-vest including front and rear side portions and a connecting shoulder portion, and adjustable straps connecting said front and rear side portions along the lower portions of their edges at the outer side to form an arm opening, an inverted U-shaped metal bow attached to the half-vest and positioned over the patient's shoulder and engaging the body of the patient at front and back with its free ends to relieve the half-vest fitted shoulder of support pull, means for retaining the half-vest against movement while in position, and means engaging the arm of the patient on the injured side and adjustably connected at fixed points.

- to the half-vest for supporting and retaining the injured shoulder in a plane higher than the other shoulder.
2. In a clavicle apparatus, the combination with a half-vest adapted for application to the side of the patient opposite the broken clavicle, an inverted U-shaped metal bow attached to the half-vest and positioned over the patient's shoulder and engaging the body of the patient at front and back with its free ends to relieve the half-vest fitted shoulder of support pull, means for retaining the half-vest against movement while in position, and means engaging the arm of the patient on the injured side and adjustably connected at fixed points to the half-vest for supporting and retaining the injured shoulder in a plane higher than the other shoulder.
3. In a clavicle apparatus, the combination with a half-vest adapted for application to the side of the patient opposite the broken clavicle, of means for retaining the half-vest against movement while in position, an elbow sling adapted for application to the arm of the patient on the injured side, a single adjustable strap connected to the elbow sling and passing diagonally upward across the back of the patient and connected at a high point to the half-vest, and two adjustable straps connected at high and low points respectively at the front of the elbow sling and passing across the front of the patient and attached at low and high points respectively to the half-vest for moving the elbow inwardly and forwardly to throw the injured shoulder backwardly and outwardly and to elevate and retain the injured shoulder a slight distance above the other shoulder.
4. In a clavicle apparatus, the combination with a half-vest adapted for application to the side of the patient opposite the broken clavicle, of means for retaining the half-vest against movement while in position, an elbow sling adapted for application to the arm of the patient on the injured side, an arm band adapted for application to the arm of the patient on the injured side, an axilla pad attached to said arm band, and an inelastic strap extending across the patient's back from the arm band and having adjustable connection with the half-vest for drawing the shoulder backward, a single adjustable strap connected to the elbow sling and passing diagonally upward across the back of the patient and connected at a high point to the half-vest, and two adjustable straps connected at high and low points respectively at the front of the elbow sling and passing across the front of the patient and attached at low and high points respectively to the half-vest for moving the elbow inwardly and forwardly to throw the injured shoulder backwardly and outwardly and to elevate and retain the injured shoulder a slight distance above the other shoulder.
5. In a clavicle apparatus, the combination with a half-vest adapted for application to the side of the patient opposite the broken clavicle, of means for retaining the half-vest against movement while in position, an elbow sling adapted for application to the arm of the patient on the injured side, an arm band adapted for application to the arm of the patient on the injured side, an axilla pad attached to said arm band, and an inelastic strap extending across the patient's back from the arm band and having adjustable connection with the half-vest for drawing the shoulder backward, a single adjustable strap connected to the elbow sling and passing diagonally upward across the back of the patient and connected at a high point to the half-vest, and two adjustable straps connected at high and low points respectively at the front of the elbow sling and passing across the front of the patient and attached at low and high points respectively to the half-vest for moving the elbow inwardly and forwardly to throw the injured shoulder backwardly and outwardly and to elevate and retain the injured shoulder a slight distance above the other shoulder.
6. In a clavicle apparatus wherein is provided a support body mountable over the sound shoulder, and means for supporting the injured member therefrom, an inverted U-shaped bow carried by the support body and disposed to press against the chest and back of the wearer at its free ends alone thereby to relieve the said sound shoulder of support pulls.
7. In a clavicle apparatus, a half-vest comprising front and back rectangular portions joined at their upper ends and along the lower portions of their edges at the outer side to form an arm opening through the upper part of those edges, and open at the inner side and lower edges to form a body receiving opening, said half-vest having a receiving pocket formed therein and extending down front and back portions and over their joined ends, and an inverted U-shaped bow removably mounted in the pocket with its free ends alone disposed to press against the chest and back of the wearer, whereby to relieve the half-vest fitted shoulder of support pull, a strap secured to and depending vertically from a portion of the half-vest at the front, and a forearm sling detachably and adjustably secured to said strap.
- In testimony whereof I have hereunto subscribed my name.
- WILLIAM C. MACDONALD.
